United States Patent Office

Des. 178,355
Patented July 31, 1956

178,355

SECRETARY

Abe J. Gaines, Glencoe, Ill., assignor to Saginaw Furniture Shops, Inc., Chicago, Ill., a corporation of Michigan

Application January 27, 1956, Serial No. 39,940

Term of patent 14 years

(Cl. D33—7)

Fig. 1.

Fig. 2.

Fig. 2 is a front perspective view thereof taken from the opposite side and illustrating the secretary in an open condition.

I claim:

The ornamental design for a secretary, substantially as shown.
